UNITED STATES PATENT OFFICE.

WINSLOW R. PARSONS, OF SAN DIEGO, CALIFORNIA.

DEVICE FOR ADJUSTING CASEMENT WINDOWS.

Application filed February 3, 1926. Serial No. 85,614.

The prime object of this invention is to provide an improved retaining means in combination with windows having an out-swung sash, an inner sash and an adjusting rod adapted to be operated inwardly from the inner sash for opening the outer sash, said means being operable for holding the rod in adjusted position in a manner which will prevent the shaking of the window by the wind from working said rod loose.

It is further an important object of this invention to provide in a device of the above type a retaining means for adjustably wedging and tightening the adjusting rod against lateral movement and so that it cannot work loose.

1005. Other and further important objects of this invention will be apparent from the disclosures in the specification and accompanying drawings.

The invention in a preferred form is illustrated in the drawings and hereinafter more fully described.

On the drawings:
25 Figure 1 is a fragmentary perspective view with parts omitted taken from the inside of a casement window having associated therewith a device embodying this invention, and showing the casement window in open position.
30

Figure 2 is a fragmentary enlarged detail cross-sectional view with parts omitted taken at the line II-II of Figure 1 and showing the casement window in closed position.

Figure 3 is an enlarged horizontal sectional view with parts omitted taken at the line III—III of Figure 1 and showing the basement window in closed position.

Figure 4 is an enlarged fragmentary detail vertical section with parts omitted and parts in elevation taken at the line IV—IV of Figure 2.

Figure 5 is a fragmentary enlarged detail vertical section with parts omitted and parts in elevation taken at the line V—V of Figure 2.

As shown on the drawings:

50 Numeral 1 represents the vertical sides of a window frame secured in a wall of a building and having a sill 2. The vertical elements 1 are provided with inner and outer vertical recesses 3 and 4 respectively affording means for containing an outer window sash 5 and an inner screen sash 6. The sashes 5 and 6 may 55 be either window sashes or screen sashes without departing from the spirit of this

invention. The outer sash 5 is in this instance hinged by means of right-hand hinges 7 to the window frame and is adapted to swing outwardly to assume the dotted line position shown in Figure 3. It is to be understood however, that this invention would be equally adapted to be used in case the sash 5 were hinged at the left and adapted to swing to the left instead of to the right as shown. Positioned intermediate the sides 1 at the lower inner edge of the sash 5 is a bracket 8.

In the embodiment shown the window is comparatively narrow but in case the window were wider as would usually be the case the bracket 8 and parts associated therewith would be positioned relatively closer to the right side 1 of the window. 70

The bracket 8 is formed from a single sheet of metal and is provided with a pair of horizontal, in-struck, integral arms 9, which are connected by a vertical pin 10. The pin 10 extends through the outer end of a hinged round rod 11 and forms a pivotal outer connection therefor. The inner sash 6 has provided therethrough at its lower edge inwardly of the bracket 8 and adjacent thereto when the sashes are in closed position a central horizontal recess 12 which extends upwardly from said edge for receiving therethrough the rod 11. The rod 11 is provided in two sections, the longer section being at its inner end and provided with a suitable integral upwardly bent portion 13 for a handle and stop. The inner section of the rod 11 is suitably hinged to the outer section thereof by a pin 14 as shown in Figure 2, the inner end of the outer section of the rod having a flat reduced portion 15 which extends into a horizontal central slot 16 in the inner section of said rod. The pin 14 is mounted in the slot 16 and extends through the portion 15 for pivotally connecting the two sections of the rod 11 together. Inwardly of the recess 100

12 and adjacent thereto on the sill 2 is mounted a bracket 18. The bracket 18 is formed from a single sheet of metal and is provided with downwardly struck sides 19 and 20 which are outwardly flanged at their lower ends, the flanges thus formed being apertured to receive holding screws 21 which extend into the sill 2. The bracket 18 is also provided with outer and inner downwardly bent faces 22 and 23 respectively. The faces 22 and 23 are provided with similar slotted apertures 24 and 25 respectively. The aper-

tures 24 and 25 are somewhat larger at their upper ends and tapering toward their lower ends. The apertures 24 and 25 of the bracket 18 are positioned in alignment with the recess 12 and are adapted to receive therethrough the rod 11. The outer aperture 24 is slightly larger in width than the aperture 25 for reasons that will be apparent from the description of the operation. A vertical screw 26 is threaded in the top of the bracket 18 and is provided with a winged head to permit manual adjustment thereof.

In the operation, let us assume that the casement sash 5 is in the closed position shown in Figure 3 and it is desired to open the same. The screw 26 may be manually loosened, the inner section of the rod 11 swung into alignment with the apertures 24 and 25 and the rod 11 pushed outwardly therethrough.

When the rod 11 is pushed outwardly the outer sash 5 will assume the dotted line position shown in Figure 3, the two sections of said rod automatically forming an angular position with each other the angularity of which varies as said rod is pushed outwardly.

The rod 11 may, however, be stopped along its path of movement through the bracket 18 and secured therein by turning the screw 26 downwardly. The apertures of said bracket being contracted at their lower ends, the rod 11 may be more securely held therein by reason of the contacts which the lower portions of the two sides of the aperture 25 make at the two diverse points 27 and 28

(Figure 4) with the lower periphery of the rod 11. With the foregoing construction the outer casement window may be efficiently adjusted without raising the inner sash. By reason of the hinged construction of the rod

11 an elaborate swiveled support for the bracket 18 is not necessary. It will also be apparent that the inner section of the rod 11 may be conveniently bent out of the way in a position parallel with the window frame as shown in Figure 3.

The recess 12 extending from the lower edge of the inner sash the latter may be raised or lowered without interfering with the device in any way.

While the retaining means embracing the bracket 18 is shown in connection with a particular form of casement windows it will be obvious to those skilled in the art that said means may be used in any form and is particularly adapted for use where a round adjusting rod is used.

I am aware that many changes may be made and numerous details of construction may be varied through a wide range without departing from the principles of this invention and I therefore do not purpose limiting the patent granted hereon otherwise than necessitated by the prior art.

I claim as my invention:

The combination with a window frame, of a sash hingedly mounted thereto, a sectional rod pivotally secured to said sash, a bracket stamped from sheet metal to define upstanding sides, secured to said window frame, there being aligned tapered slots in said upstanding sides to slidably receive said rod, and an adjustable screw associated with said bracket to selectively wedge said rod in said slot.

In testimony whereof I have hereunto subscribed my name.

WINSLOW R. PARSONS.
